MUSCLE CONTRACTING APPARATUS

Reginald E. G. Dewar, Oakland, Calif., assignor
to Arthur Matthews, San Francisco, Calif.

Application November 15, 1938, Serial No. 240,505

5 Claims. (Cl. 128—422)

My invention relates to muscle contracting apparatus, and more particularly to a device for producing artificial exercise, whereby muscles may be rhythmically contracted and relaxed. 5 Among the objects of my invention are: To provide an apparatus for producing artificial exercise; to provide an apparatus which will rhythmically contract and relax muscles; to provide a device operating at relatively low potentials for 10 creating an artificial muscle contraction and relaxation; and to provide a simple and efficient electrical device for producing artificial exercise.

Other objects of my invention will be apparent or will be specifically pointed out in the description forming a part of this specification, but I do not limit myself to the embodiment of the invention herein described, as various forms may be adopted within the scope of the claims.

Other broad objects may be more readily understood by direct reference to the drawing, which is a schematic circuit diagram of one preferred form of my invention.

I provide an oscillator tube 1 of the triode type, controlled by a single tuned circuit 2 connected to tube 1 to create an oscillator of the "Hartley" type. Grid 3 is maintained at the proper bias by a bias assembly comprising the usual resistor 4 and grid condenser 5. Anode 6 of tube 1 is provided with a positive potential from a source, not shown, by wire 7.

An intermediate tap 8 from oscillating circuit 2 is connected to cathode 9 of tube 1, and the negative connection to the tube is provided by wire 10 connected to one end of tuned circuit 2 and to the negative end 11 of the source, not shown. Tuned circuit 2 is coupled to grids 12 of amplifying tubes 13, connected in parallel, by a connection from center tap 8 on tuned circuit 2, through a blocking condenser 14. Cathodes 15 of amplifier tubes 13 are preferably indirectly heated, and both are connected by wire 16 to negative source terminal 11. Anodes 17 of the amplifying tubes are connected in parallel then through primary 18 of output transformer 19 to an additional source of positive potential, not shown, by connection to terminal 20 thereof. An equilibrium leak resistor 23 may be utilized if necessary to prevent accumulative blocking of grids 12.

Amplifier tubes 13 preferably use accelerating grids 21, both connected in parallel to a positive bias source indicated by terminal 22. The output of the amplifier tubes is controlled by a "Kipp" or relaxation oscillator 25, preferably of the gaseous diode type. One element of this tube 55 25 is connected to negative source terminal 11

and the other element is connected through amplifier grid condenser 26 and amplifier grid leak 21 to grids 12 of the amplifier tubes. The frequency of the relaxation oscillator tube 25 is controlled by a shunt condenser 28 and fixed resistors 29, 29 in series with a variable resistor 30, all resistors being in series with a relaxation oscillator tube source, not shown, indicated by positive terminal 31. I prefer to utilize series glow tubes across the source of power for relaxation 10 oscillator 25 in order to stabilize the voltage of the source, as is well known in the art.

The output of transformer 19 is taken from secondary 34 thereof through output circuit 35 which feeds a potentiometer resistor 36, the varying contact 37 of the potentiometer being connected to terminals 38 on an applicator connection board which also carries spaced pairs of terminals 39, each pair being connected together and connected to one end of potentiometer resistor 36 through variable resistors 40.

Either one of terminals 38 constituting one side of output circuit 35, is utilized as a connection to a central applicator electrode 41 which is preferably applied to the spine of a patient. As is customary with such electrodes, the metal sheet used is generally covered with an absorbent cloth covering moistened with a bicarbonate of soda solution to provide good contact with the skin. 25

Terminal pairs 39 are used to supply connections to a plurality of spaced pairs of lateral electrodes 42a, 42b and 42c, and these lateral electrodes are preferably positioned one in each pair on each side of the central electrode on the patient. For example, pair 42a may be positioned on the arms of the patient, pair 42b may be positioned on the hips of the patient, and pair 42c may be positioned on the legs of the patient. 35

Having thus described the circuit set-up, I will now describe a preferred mode of operation.

I have found, for example, that the voltage in the output circuit 35 will be sufficient to cause muscle contraction between the limits of five and thirty volts when oscillator 1 is adjusted to have a frequency within the audible range, preferably between one and three thousand cycles per second. Under these circumstances, grids 12 of the amplifier tubes would ordinarily be energized and the power fed directly into the output circuit to the patient continuously, if it were not for the action 40 of the relaxation oscillator 25.

If the circuit as described is examined, it will be found that grids 12 are isolated by condensers 14 and 26. Under these conditions, due to acceleration of electrons during amplification operation, 45

with a leak of charge through equilibrium resistor 23 less than the rate of electron accretion, the grids 12 will become negatively blocked and the amplifier tubes will cease to amplify and no energy will be passed into output circuit 35. However, when energy is supplied to relaxation oscillator 25 slowly through resistors 29 and 30, shunt condenser 28 will gradually charge up positively until the potential is sufficient to break down the gas in relaxation oscillator 25, whereupon the tube 25 will ignite and discharge condenser 28, and this periodical charge and discharge of the relaxation oscillator 25 will continue cyclically at a frequency as determined by the values of resistors 29 and 30 and capacity 28. Accumulative blocking is prevented by resistor 23, although this resistor may sometimes be dispensed with if sufficient leakage takes place through condensers 14 and 28 to prevent such long period blocking. However, inasmuch as grid condenser 26 is connected to shunt condenser 28 and to tube 25 on the positive side thereof, the potential across capacity 28, as it rises, will overcome the cut-off bias of grids 12 and place the amplifier tubes in condition to transmit energy therethrough from oscillator 1 into output circuit 35. I prefer to adjust the frequency of relaxation oscillator 25 to a value of a few cycles per minute, such as, for example, twenty per minute, although it will be obvious that this can be varied by varying variable resistor 30.

Thus, in output circuit 35 there will exist a rhythmical flow of alternating current at the frequency of oscillator 1, this flow varying from maximum to zero at a rate of, for example, twenty cycles per minute. When all applicator electrodes are applied to a patient and both oscillators energize, the flow of energy into the patient may be regulated by potentiometer 36 and variable resistors 40, so that complete contraction of the muscles will take place during the time energy is present in output circuit 35, and relaxation of the muscles may take place when amplifier tubes 13 are blocked.

45 Thus, I have provided means for rhythmically contracting and relaxing muscles to provide artificial exercise, and at a relatively low potential. I have found that at the frequencies and potentials utilized, that the contractions produced thereby are not painful, but on the contrary are highly effective for many purposes.

In order that the patient may be fully protected from the voltages of the oscillator system, I prefer to thoroughly insulate secondary 34 from primary 18, and have shown specifically a wide spacing thereof, indicating that purpose in the drawing.

I claim:

1. Muscle contracting apparatus comprising an electron discharge oscillator tube, circuit means connected to said oscillator tube to maintain said tube in continuous and substantially constant oscillation at a frequency within the audible range, an electron discharge amplifier tube having control means including a grid fixedly biased to cut-off current through said amplifier tube and having the control means thereof connected to the output of said oscillator tube, a time constant oscillator also connected to the control means of said amplifier tube, and operating at a frequency materially lower than the frequency of said continuously operating oscillator tube and with sufficient power to cyclically overcome the fixed bias on the grid of said amplifier tube to cause said amplifier tube to pass current and to amplify the output of said continuously operating oscillator in accordance with the waveform of said time constant oscillator tube, and applicator electrodes connected to the output of said amplifier tube.

2. Apparatus in accordance with claim 1 wherein the continuously operating oscillator is tuned to a frequency between one thousand and three thousand cycles per second, and the time constant oscillator is tuned to operate at a frequency on the order of twenty cycles per minute.

3. Apparatus in accordance with claim 1, wherein an isolation transformer is positioned in the output circuit between the amplifier tube and the application means.

4. Muscle contracting apparatus comprising an electron discharge oscillator tube, circuit means connected to said oscillator tube to maintain said tube in continuous and substantially constant oscillation at a frequency within the audible range, an amplifier tube having an input including a control grid and an output, means for isolating the grid of said amplifier tube to cause self-blocking of the output of said amplifier tube, means for connecting the output of said continuously oscillating tube to the control grid of said amplifier tube, a time constant oscillator tube, a time constant circuit connected to said latter tube to maintain the period of oscillation thereof at a frequency on the order of twenty cycles per minute, means for applying the output of said time constant tube to the grid of said amplifier tube in a direction overcoming the self bias of said grid, and applicator electrodes connected to the output of said amplifier tube.

5. Apparatus in accordance with claim 1 wherein said amplifier tube control means is a single grid.
